UNITED STATES PATENT OFFICE.

GEORGE HENRY PARFITT, OF OAKLAND, CALIFORNIA.

MOISTENER.

1,188,310.

Specification of Letters Patent. Patented June 20, 1916.

Application filed March 14, 1916. Serial No. 84,163.

To all whom it may concern:

Be it known that I, GEORGE HENRY PARFITT, a citizen of the United States, residing at Oakland, in the county of Alameda 5 and State of California, have invented a new and useful Moistener, of which the following is a specification.

This invention relates to an improved moistener for use in sealing envelopes, applying stamps, sealing wrappers, applying stickers, or for any other use, wherein it is desired to moisten for sealing, or the like.

An object of the present invention is to provide a relatively small device, which may 15 be easily held in the hand and applied to the surface to be moistened, which has a wiper held at a downwardly inclined angle, so that the body of the moistener need be tilted at but a slight angle, and which has 20 the wiper so arranged upon the end of the moistener that when the moistener is placed flat upon a table, desk, or the like, the wiper is held out of contact with the table or desk, so as not to wet the same.

25 Further objects of the invention are to provide a moistener with a hollow body adapted to contain a relatively large amount of water to be supplied to the wiper continuously, to provide a sanitary device, to 30 provide a device of simple construction having relatively few parts which cannot easily get out of order, to provide a device which has an air valve for admitting air to the body, and to thus admit of the free out- 35 ward flow or absorption of the water by the wick or wiper, and which has the air valve so disposed in the end of the device that the same may be set upright on end, if desired, and without any danger of opening the 40 valve or releasing the water in the body.

A still further object of this invention is to provide a moistener of this character with a valve which may be opened by the finger, so as to admit air into the upper end 45 of the body to thus admit of the quick saturation of the wiper after the device has stood without use for considerable time.

Other objects and advantages of the invention will be brought out in the following specific disclosure of the present preferred embodiment of the invention, the same being illustrated in the accompanying drawing, wherein—

Figure 1 is a longitudinal central section view, taken through a moistener constructed according to this invention, show-

ing the same in position on a flat surface. Fig. 2 is an outer end elevation of the same, showing the position of the wick or wiper. Fig. 3 is a transverse sectional view, taken 60 through the forward end of the moistener on the line 3—3 of Fig. 1, and looking forwardly in the direction indicated by the arrow. Fig. 4 is an inner end elevation of the moistener. Fig. 5 is a transverse sectional 65 view, taken on the line 5—5, through the inner end of the device and looking in the direction of the indicating arrow.

Referring to this drawing, wherein like parts are designated by similar numerals 70 of reference throughout the several views, 10 designates the body of the improved moistener, which, in the present instance, is shown as of cylindrical contour, and which is preferably internally threaded at its outer 75 or lower end. This body 10 is adapted to contain a quantity of water, or other suitable fluid used in moistening surfaces for sealing, or other purposes. The outer end of the body 10, which is the lower end 80 thereof when in use, is provided with a cap 11. The cap 11 is in the form of a disk or plate substantially circular in contour and engaging flat against the outer end of the body 10 to close the same. The cap 11 85 has an inwardly extending annular flange 12 which is preferably externally threaded for detachable engagement with the threaded outer end of the body 10.

For the purpose of maintaining the cylindrical body 10 from rolling when placed upon a flat surface, the cap 11 is provided with a base flange or foot 13. The foot 13 comprises an enlargement at the lower side of the disk cap 11 provided with a straight 95 lower edge adapted to lie flat upon the supporting surface, and which extends laterally from the cap 11, as shown in Fig. 2.

As shown in Fig. 1, this foot or base flange 13 extends slightly below the adjacent side of the body 10 to elevate the outer end of the body and hold it from rolling. By this peculiar formation of the cap 11, the latter may be screwed tightly into the outer end of the body 10 to seal the same and prevent escape of the fluid in the body. As the threads of the flange 12 and the body 10 become worn, it is readily understood that the cap 11 may be turned to a greater extent into various angular positions upon 105 the end of the body, and the foot 13 need not register at all times with one predeter-

mined side of the body. The foot, therefore, is carried by the cap, so that the cap will always be held in upright position, irrespective of its angular adjustment upon 5 the end of the body.

The cap 11 carries a wiper 14 in the form of a strip of absorbent or wick material, which passes through an inclined opening 15 in the cap at the base of the flange 12 and 10 immediately over the foot 13. This opening 15 is in the form of a transversely extending slot of substantial width, and which has its walls inclined downwardly and forwardly, so as to direct the outer end of the wiper 14 15 downwardly and outwardly, as shown in Figs. 1, 2 and 3. This wiper 14 projects beyond the face of the cap 11 to an extent which admits of the easy contact of the wiper with the surface to be moistened, but 20 which, when the moistener lies flat upon a surface, will be raised above the surface, so as not to wet the same or become soiled by contact therewith. The inner end of the wiper 14 extends into the cap 11 a short distance 25 and is there immersed in the fluid contents of the body.

The disk cap 11 has at its top edge, or the edge diametrically opposite to the foot 13, a straight boss 26 rounded for rubbing contact 30 with the flap of an envelop, or the like, in sealing or applying the same. The foot 13 and the boss 26 extend substantially at a tangent across the diametrically opposite sides of the cap 11. The boss 26 may be 35 quickly brought into position for use by merely turning the moistener over in the hand.

The inner end of the body, which is the upper end of the device when in use, is 40 closed by a cap 16. As shown in Figs. 1, 4 and 5, this cap 16 is preferably of circular contour and engages flat against the inner end of the body 10 to close the same. The cap 16 has its inner end reduced to provide 45 a plug portion 17, which is fitted into the lower inner end of the body 10.

The cap 16, like the cap 11, may be permanently secured in the end of the cylinder or may be detachably mounted therein. In 50 the present drawing, the cap 16 has the plug portion 17 thereof brazed or serrated in the cylinder, and is intended to be permanently attached thereto. The cap 11 is shown detachable as it carries the wick 14, 55 and the removal of the cap 11 admits not only of the easy filling of the body 10, but also admits of the easy and quick adjustment and renewal of the wick 14.

The outer face of the cap 16 has a con- 60 caved recess 18 at its central portion into which projects the outer end of a stem 19, which slidably engages through an axially formed opening in the cap 16. At the inner end of this axial opening is a valve 65 seat 20 against which engages a valve 21,

pressed against the seat by a spring 22. The valve 21 is housed within a counter-bore or pocket 23 formed in the inner or plug portion of the cap 16. The counter-bore 23 is of a size slightly larger than the 70 diameter of the valve 21 to admit the passage of air about the edge of the valve, when the same is open.

Air vents or passages 24 are arranged laterally of the axial opening in the cap 16, 75 and extend from the concaved recess 18 to the valve seat 20 for the purpose of preventing the clogging up of the vents 24 when the body 10 is set up on end to rest on the cap 16, and for normally closing the inner 80 ends of the vents 24 by the valve 21. It is, of course, understood that any number of these vents 24 may be provided in the cap 16.

A pin 25 is secured diametrically through 85 the inner end of the cap 16, the pin traversing the pocket or counter-bore 23, and having suitably secured thereto, the inner end of the spring 22 to thus hold the spring against the valve 21. The stem 19 of the 90 valve is of such length that when the valve is seated, as shown in Fig. 1, the outer end of the stem 19 lies within the plane of the end of the device, so that the valve will not be unseated when the body 10 is set in 95 upright position on end. However, the depression 18 is of such size as to admit the thumb or finger of the operator for pressing the button or outer end of the stem 19 to unseat the valve 21, and admit air 100 through the vents 24 and into the top of the cylinder 10.

With a moistener of this construction, it is readily understood that the cap 11 may be quickly removed and replaced upon the 105 outer end of the cylindrical body 10 by merely screwing the cap into or out of engagement with the body. This admits of the quick handling of the device in filling and cleaning the same, and in replacing 110 new wicks or other absorbents when necessary. The base flange or foot 13 on the cap 11 provides a positive means for preventing the rolling of the body 10, when it is placed down upon a flat surface, and provide a means which does not depend upon any peculiar adjustment of the caps upon the ends of the cylinder, or any peculiar construction of the cylinder itself. When the moistener stands for a considerable length of 115 time without use, the outer end of the wiper 14 naturally becomes dry.

When the moistener is picked up for use, it is not necessary to shake the same, and to hold it in upright position for a considerable length of time in order to work the water down into the wiper. It is only necessary to insert the thumb or finger into the depression 18 and push the valve stem 125 19 inwardly to unseat the valve and admit 130

air to the body. When the air is admitted to the body, the water will then be very quickly and readily absorbed by the wiper 14.

When the adhesive on the flap of the envelop, or other surface, has been moistened and the flap turned down, the device may be easily turned over in the hand to place the straight boss 26 at the bottom of the cylinder, and the boss rubbed over the applied flap by the same reciprocating movement employed in moistening the adhesive.

What is claimed is:—

A moistener comprising a cylinder, a removable cap threaded into the outer end 15 of the cylinder, a second cap in the inner end of the cylinder and having a spring pressed air valve therein with a stem extending outwardly from the valve and terminating within the plane of the outer end

of the cap to provide a press button to open 20 the air valve, and a wiper carried through the removable cap and projecting downwardly and outwardly therefrom, said detachable cap having a transversely extending flange at its lower side beneath the wiper 25 to hold the same upwardly out of contact with a supporting surface, and to prevent the rolling of the cylindrical body, and also having a straight boss extending substantially tangentially across the upper side of 30 the detachable cap to provide a sealing edge.

In testimony that I claim the foregoing as my own, I have hereto affixed my signature in the presence of two witnesses.

GEORGE HENRY PARFITT.
